INVENTOR
Harold Rowntree
BY his ATTORNEYS Darby & Darby

UNITED STATES PATENT OFFICE.

HAROLD ROWNTREE, OF PASS CHRISTIAN, MISSISSIPPI, ASSIGNOR TO NATIONAL PNEUMATIC COMPANY, OF NEW YORK, N. Y., A CORPORATION OF WEST VIRGINIA.

UNIT DOOR-CONTROL SYSTEM.

Application filed June 4, 1921. Serial No. 475,140.

To all whom it may concern:

Be it known that I, HAROLD ROWNTREE, a citizen of the United States, residing at Pass Christian, in the county of Harrison,

5 State of Mississippi, have made a certain new and useful Invention in Unit Door-Control Systems, of which the following is a specification.

This invention relates to unit door control systems for cars.

The object of the invention is to provide a unit door control system for cars, and is particularly directed towards the provision of means whereby the doors may be power 15 actuated in their closing movements, but may be either free for manual operation individually in their opening movements, or power actuated to open position, as may be desired.

20 A further object of the invention is to provide a system of door control wherein all of the doors are locked in their closed positions, a means common to all of the door locks being provided to effect a simultaneous release of all the door locks.

25 A further object of the invention is to provide a unit door control system of the nature referred to whereby, when the doors are unlocked, any individual door may be opened either manually or by power operating mechanism, the power operating mechanism for opening the door being under suitable automatic control.

30 A further object of the invention is to provide a unit door control system of the nature referred to, having combined therewith a signalling means to indicate when all of the doors occupy their closed and locked positions.

35 Other objects of the invention will appear more fully hereinafter.

The invention consists substantially in the construction, combination, location and relative arrangement of parts, all as will be 40 more fully hereinafter set forth, as shown in the accompanying drawings, and finally pointed out in the appended claims.

45 In the accompanying drawings Fig. 1 is a diagrammatic view illustrating the application of a unit door control system to a plurality of doors in accordance with the principles of my invention.

50 Fig. 2 is a similar view in plan, illustrating a modified door operating mechanism 55 suitable for use in carrying out my invention.

Fig. 3 is a broken view in elevation, illustrating a form of power actuated mechanism suitable for use in carrying out my invention.

According to existing practice in the operation and control of doors on subway, elevated, and other passenger or street car systems, the control of each door in its opening and closing movements is supervised or effected by a guard stationed in close proximity to the door to be operated, the operation of each door being accomplished according to the requirements of the traffic. According to more recent development of the system of door operation and control, the 60 tendency has been to increase the number of doorways and doors, and to decrease the number of guards or attendants so as to place under the supervision and control of each guard the operation and control of a 65 number of doors, the guard, sometimes, effecting the control of doors of other cars besides the one on which he is stationed. In the practical operation of this multiple unit control system as now employed in practice 70 the operations of the doors are accomplished 75 more or less by schedule, all of the doors being opened when the car or train arrives at a station platform, and after a predetermined interval, the doors being closed 80 through the control of the guards, each guard endeavoring as best he may from a distance to judge when to close each door under his control, or relying upon the safety shoes with 85 which the front edges of doors in modern 90 practice are equipped to prevent injury to any passenger that may be struck by the advancing edges of a door in closing.

One serious objection to this method of control is, particularly in the case of cars 95 or trains operating in the open air, as in the case of elevated trains, for example, that it may often happen that all the doors of a car or train will be opened on the arrival of the car or train at a station or platform, thereby admitting rain, snow or other atmospheric elements, or causing the cars to become chilled, where perhaps no passengers desire to alight from or to board the car.

100 In accordance with my present invention, I propose to provide a unit door control system in which control of the door operation is effected automatically, and not by the interposition of a guard or guards, particularly with respect to the closing movements 105 110

of the door, such movements being effected, in accordance with my invention, through the operation of power driven mechanism, which, if desired, may be controlled through 5 suitable safety devices to prevent injury to a passenger in case the closing door should strike a passenger in its closing movements. And, with reference to the opening movements of the door, I propose, in accordance 10 with my invention, to leave each door free to be moved manually towards open position by persons either on the car or on the station platform, or to control power actuated means for opening any individual door 15 by the act of persons either on the car or on the station platform.

In connection with this system, and forming part of my invention, I propose to employ a lock device for each door to lock the 20 same in its closed position, the locks for all of the doors having means common to all of them to effect the simultaneous unlocking of the locks. Also, in accordance with my invention, and forming a part of the same, I 25 propose to employ a signalling system which will indicate to the motorman, for instance, when all the doors are closed and locked in their closed positions, thereby indicating when it is safe for the car or train 30 to be put into motion.

Important and essential features of a system of unit door control embodying my invention should include, first, provision of means to indicate when all of the doors 35 throughout the system are closed and locked in their closed positions, to the end that the car or train will not be started until the doors are closed and locked. Secondly, the provision of doors suitable for passengers to 40 use in boarding or alighting, and, in addition thereto, means for unlocking all of the doors when the train stops. Thirdly, the only doors that are opened are those which the passenger or passengers throughout the 45 train desire to use. In other words, if at any door there is no passenger desiring to get on or off of the train the door remains closed. And, fourthly, passengers can be educated to open the doors they desire to 50 use but can not be expected to close the same, and therefore the closing must be effected efficiently, speedily, and preferably by power devices, and where a single control of the entire train is desired by a single 55 operation throughout the entire train for effecting the closure of all doors that have been opened without in any way deranging or affecting the doors that have not been 60 opened other than to effectively lock the same in their closed position. Therefore, in accordance with my invention, I provide a pneumatic engine for each door of the type where the engine is controlled by two electro-magnets, so that when one is energized 65 and the other deenergized the door opens,

and when the reverse is the case the door closes. The door cushioning means may or may not be provided in both opening and closing in accordance with the standard practice in pneumatic operated doors. I 70 further employ a collapsible shoe on the front of the door of each car so arranged that an electrical contact is made when the shoe is depressed or collapsed. I also employ a door lock and a relay magnet switch 75 for effectively controlling the operation of the system, as hereinbefore generally described. Referring specifically to the drawing, I have shown my invention in its broadest scope as applied to a system where the 80 motive power for the doors in closing is effected from a single motor 1, mounted preferably at one end of the car 2, the shaft 3 of which is provided with a wheel 4, which operates a worm 5 mounted on a shaft 6, 85 the ends of the shaft 6 being provided with sprockets 7, over which operate endless chains 8. The respective doors illustrated diagrammatically at 9 equipped with the collapsible shoes 10 at the front edge thereof, are provided in addition thereto with a lug 11, which forms a pivotal mount for a bell crank lever, one leg 12 of which is positioned to be rocked when the shoe 10 is collapsed, the other end 13 of which is provided 90 with teeth adapted to engage the chain 8 to be moved thereby, and normally held in engagement therewith by a spring 14. With this arrangement it will be seen, assuming that the top chain 8 is moving 95 toward the left, in the arrangement shown in Fig. 3, the door is moved towards the left to its closed position, but in the event the door encounters an obstruction in its closing movement sufficient to compress the shoe 10 100 relative to the door 9, the bell crank lever 12 is rocked upwardly, thereby rocking downwardly the portion 13 thereof, and in consequence disengaging against the action of the spring 14 the teeth carried thereby 105 which engage the chain 8. With the shoe compressed the door may be moved to its completely open position, or may be held in a stationary position. As soon, however, assuming that the motor 1 is continuously operating as the shoe 10 assumes its extended position, the teeth of the leg of the bell crank lever again engage chain 8 and the door is moved on to its closed position. When the shoe collapses, either by reason of 110 meeting an obstruction or when the door is closed, it will move longitudinally and upwardly, as is well known to the art and as is disclosed in my Patent No. 1,200,826, October 10, 1916. This will cause the levers 12 and 13 to rock as stated above, and teeth of lever 13 will disengage leaving the power 115 means, or chains 8, free to move.

It will be apparent that where it is desired to move the door in the opposite direc- 120

tion from that just described, that may be effected by having the bell crank levers 12, 13, engage the lower chain 8, the construction and operation being substantially identical with that just described.

The door lock employed in accordance with my invention consists similarly of a bell crank lever, one leg 15 of which is normally pressed towards the door 9 by any suitable means, for example, by means of spring 16, the opposite leg 17 thereof forming the armature of magnet 18, and mounted so that when the magnet 18 is energized the leg 17 is drawn towards the same, which 15 rocks the bell crank about its pivot 19, and lifting the detent or leg 15 thereof from behind the door enabling the door to be opened manually as hereinbefore described. Simultaneously therewith the leg 17 of the bell 20 crank lever also opens the circuit which is normally maintained between contacts 19' and 20, and which, if desired, may be included in the circuit of the signal device and utilized as will be more fully hereinafter 25 described to notify the motorman, or any other operator, that the door has been closed and locked. It will be readily understood that if the door 9 has been opened but a short distance, even though the magnet 18 is 30 deenergized, the door itself prevents the detent from slipping back into place until the door has been closed. Referring to Fig. 1 of the drawing, I show an amplification of the invention thus far described, and wherein 35 certain advantages are obtained, by employing separate door motors for each door, and wherein the door 9 is equipped with a safety door shoe 10^a of a slightly different construction from that hereinbefore described, due 40 to the fact that in this arrangement the safety control is effected electrically rather than mechanically. Each door is provided with a motor 30, preferably of the pneumatic type commonly employed in door operation, the operation of which actuates a door rod 31 which is slidably mounted on a rod 32 carried at the rear edge of the door to thereby control the opening and closing movements of the door. Each door motor 45 is controlled by two suitable magnet valves, one thereof, namely 33, being what I will term opening magnet valve, and the other 34, being the closing magnet valve, it being readily understood by those skilled in the 50 art that when magnet 33 is energized the motor is operated to open the door, and that when the magnet 34 is energized the motor is operated to close the door. The door shoe 10^a in this arrangement is of the electrical 55 type, that is, when the shoe is collapsed a normally opened circuit is closed. This may be effected in any suitable way, for example, by having one terminal of the circuit enclosed in a flexible rubber casing, the terminal comprising a conducting rod 35 posi-

tioned within the casing, and the other terminal comprising a flexible spring member, such coiled spring 36 surrounding the rigid rod 35 so that when pressure is exerted against spring 36 contact is established between spring 36 and rod 35. In the arrangement shown current is supplied to the system from a supply line 40 controlled by any suitable switch device positioned to be readily controlled by the operator 41. The 70 supply line 40, it will be understood, extends through all of the doors suitable for use at any particular station, or on one side of the car, and where more than one car is employed throughout the entire train, it 75 may be termed a train line. Each of the doors is equipped with what I will term a control magnet 42, which magnet is connected on one side to ground as indicated, and on the other side to the train line 40. 80 Each magnet 42 controls an armature 43 pivoted intermediate its ends and normally retained in any suitable manner, for example, by means of spring 44 in the position which it assumes when the magnet 42 is deenergized. In this position of the armature 43 the same closes the circuit between two otherwise open circuit terminals 45, 46. Terminal 46 is connected through closing magnet 34 85 to ground, and terminal 45 is connected to terminal 47 which is normally maintained in contact with armature 48 controlled by a magnet 49. The door locking detent illustrated at 50 is mechanically moved by armature 43 to release the same, and a spring 51 90 normally tends to retain the door lock or detent in its locked position behind the rear end of the door. When the detent is in its locked position an arm 52 thereof establishes electrical circuit between contact terminals 95 53 and 54 which is a seriatim circuit passing through all of the door lock devices to a signal for the motorman at the front of the train, it being readily understood that a source of current is included in this circuit 100 whereby when all of the detents are in the position shown in Fig. 1 the circuit is then, and only then, completed, and current supplied to the signal device at the front of the train, thereby electrically signalling that all 105 of the doors are closed. When, however, the detent or lock is released by supplying current to the magnets 42 the arm 52 of the detent or lock establishes circuit connection 110 between contact terminals 55 and 56. Each contact terminal 56 is connected to a power wire 57, which, in the event that a train of cars is employed, will extend throughout the length of the train. The magnet 49 is connected to the contact terminal 55 at one terminal thereof, the other terminal being connected to the door rod 35, the armature 48 of the magnet being supplied with current from this circuit. The armature 48, when 115 the magnet 49 thereof is energized, opens the 120 125 130 135

circuit between armature 48 and contact terminal 47, and closes the circuit between armature 48 and contact terminal 60, which contact terminal is connected to opening magnet 33 of the motor 30, and thence to ground.

The operation of the system thus described is as follows:—Assuming the doors to be all in their closed position, either in the car or on the train of cars, as the case may be, and the car or train of cars comes to rest at a station, the operating switch 41 is closed which supplies current from the main 40 to all of the control magnets 42, and thence to ground. Energizing magnets 42 attracts armatures 43, thereby mechanically moving the door locks 50 out of engagement behind the doors 9. It will be apparent that beyond unlocking the doors the mere closing of the switch 41 will not affect any operation of the door motor, due to the fact that the contact terminal 60, of the opening magnet 33 thereof, remains open. Therefore no door of the train or car, as the case may be, will be open. If, however, a passenger desires to enter or leave the car, or pass through the door, such passenger grasps the handle 70 carried by the collapsible shoe 10^a and moves the same naturally in the door opening direction. This establishes the following circuit connection, power line 57, contact terminal 56, contact terminal 55, (the detent or lock 50 having been shifted by the initial actuation of the switch 41, thereby opening the signal circuit controlled by contact terminals 53 and 54, and closing the circuit between contact terminals 55 and 56), magnet switch 49, rod 35, spring 36, to ground. Energizing the magnet 49 attracts the armature 48, thereby completing the circuit through armature 48, contact terminal 60, opening magnet valve 33, thereby actuating the motor to open the same, and the motor will continue to operate as long as pressure is exerted on the door shoe 10^a, sufficient at least to cause the spring 36 and rod 35 to remain in contact with each other. It will be apparent however, that when the pressure is removed from the door shoe 10^a the door will not close but will merely remain stationary, capable of being manually pushed open by pressure on the door 9, or continued further in its pneumatic operation by again collapsing the shoe. The operator who initially unlocks the doors by operation of the switch 41, after the elapse of a reasonable amount of time, opens the switch 41, or, in other words, the switch 41 may be in the form of a push button which is held depressed a sufficient time to allow any one who desires to get off the car to reach the door and open the same before the finger is removed therefrom. As soon however as the switch 41 becomes open the

control magnet 42 becomes deenergized, allowing circuit connection to be established between contacts 45 and 46 by armature 43 operated by spring 44. Every door, the shoe 10^a of which is not collapsed at that moment, and in consequence the magnet 49 energized thereby, and which door is open, receives current through power line 57, contacts 56, 55, armature 48, contact 47, contact 45, armature 43, contact 46, closing magnet valve 34 to ground, thereby causing the motor 30 to operate to close the door in the usual well known manner. It will be apparent that where the door is already closed, due to the fact that no passenger has opened the same, the opening of the switch 41 merely results in allowing the lock 50 to assume its door locked position. If, however, the door has moved even an inch or so from its completely closed position when the locks or detents 50 were released by the initial closure of the switch 41, the operation of the door motor 30 through the energizing of its closing magnet valve 34, as above set forth, occurs. Now, during the closing movement of the door, if the door should meet an obstruction such as a passenger who has not completely entered or left the car, the door shoe 10^a is collapsed and the pressure necessary to cause the collapsing of the same is, as hereinbefore set forth, exceptionally supplied, and the circuit is again established between terminals 35, 36, to again energize magnet valve 49, open the circuit between armature 48 and contact 47, and thence to closing magnet valve 34, as above described, and establishes the circuit between armature 48 and contact 60, and thence to opening magnet valve 33, whereby the door is again caused to open until the circuit is broken between terminals 35 and 36 by the obstruction either being withdrawn or by the door withdrawing away therefrom. As soon however as the shoe 10^a becomes extended again, the switch 41 being still open, magnet 49 again becomes deenergized and armature 48 assumes the position shown in the drawing, whereby current is again supplied to the closing magnet valve, and this operation takes place rapidly, and in the succession above set forth, until no obstruction is encountered by the door, or any of the doors, and the door assumes its completely closed position, whereby spring 51 causes detent lock 50 to enter behind the door to lock the door in its completely closed position, open the circuit between contacts 55 and 56, and close the signal circuit controlled by contacts 53, 54, whereby not only is the signal to the motorman given that the door, or all of the doors, of the train are closed, but also preventing any operation from taking place if through accident or otherwise the shoe 10^a is collapsed again,

and the terminals 36 and 35 are brought in contact with each other.

It will be apparent that the structures selected for illustrating my invention here involved are largely diagrammatic, and many modifications and changes in details will readily occur to those skilled in the art without departing from the spirit and scope of my invention as defined in the 10 claims, and I therefore desire to have the foregoing description and the illustrations selected for the purpose of illustrating the principles of the invention regarded in an illustrative sense rather than in a limiting 15 sense. Having now set forth however the objects and nature of my invention, and having shown and described structures embodying the principles thereof, what I claim as new and useful and of my own invention 20 and desire to secure by Letters Patent is,—

1. The combination with a door, of power means for controlling said door, means for locking said door in closed position, normally open circuits for controlling the door opening and closing movements of said power means, means carried by the door to permit the manual opening thereof when said locking means is in neutral position, and means controlled thereby for closing the door opening 30 circuit.

2. The combination with a door, of power means for controlling said door, means for locking said door in closed position, normally open circuits for controlling the 35 door opening and closing movements of said power means, means carried by the door to permit the manual opening thereof when said locking means is rendered ineffective, and means controlled thereby for closing the door opening 40 circuit, and maintaining the same closed as long as manual effort is exerted towards door opening position.

3. The combination with a door, of power means for controlling said door, means for locking said door in closed position, normally open circuits for controlling the door opening and closing movements of said power means, a collapsible shoe carried at the front edge of said door, means carried 45 by said shoe to permit the manual operation of said door when said locking means is rendered ineffective and means controlled thereby for closing the door opening circuit.

4. The combination with a door, of power 50 means for controlling said door, means for locking said door in closed position, normally open circuits for controlling the door opening and closing movements of said power means, a collapsible shoe carried at the front edge of said door, means carried 55 by said shoe to permit the manual operation of said door when said locking means is rendered ineffective, and means controlled thereby for closing the door opening circuit 60 and maintaining the same closed as long as

manual effort is exerted towards door open position.

5. The combination with a door, of power means for closing the door, means whereby said door may be manually opened and a locking device for rendering ineffective the 70 said means, means for temporarily rendering said locking device inoperative, and means for automatically operating said locking device when the door reaches its closed position 75 from its open or partially open position.

6. The combination with a door, of a door lock, means for releasing said lock to permit the manual operation of the door, a circuit for controlling said lock releasing 80 means, a power device for controlling said door, a normally open closing circuit for actuating said device to close the door, a normally open opening circuit for actuating said device to open the door, said lock controlling both said opening and closing circuits. 85

7. The combination with a door, of a door lock, means for releasing said lock to permit the manual operation of the door, a circuit 90 for controlling said lock releasing means, a power device for controlling said door, a normally open closing circuit for actuating said device to close the door, a normally open opening circuit for actuating said device to 95 open the door, and means controlled by the opening of the circuit of said lock releasing means for closing the closing circuit.

8. The combination with a door, of a door lock, means for releasing said lock to permit the manual operation of the door, a circuit for controlling said lock releasing means, a power device for controlling said door, a normally open closing circuit for actuating said device to close the door, a normally open 100 opening circuit for actuating said device to open the door, means controlled by the opening of the circuit of said lock releasing means for closing the closing circuit, and means controlled by the door encountering 105 an obstruction in closing for opening the closing circuit and closing the opening circuits. 110

9. The combination with a door, of a door lock, means for releasing said lock to permit the manual operation of the door, a circuit for controlling said lock releasing means, a power device for controlling said door, a normally open closing circuit for actuating said device to close the door, a normally open 115 opening circuit for actuating said device to open the door, means controlled by the opening of the circuit of said lock releasing means for closing the closing circuit, and means controlled by the door encountering 120 an obstruction in closing for opening the closing circuit and closing the opening circuit and for again opening the opening circuit and closing the closing circuit when the 125 obstruction has been removed. 130

10. The combination with a plurality of doors, means to lock said doors in closed position, means for rendering said locking means ineffective, means for manually opening each door independently of the other doors, and power means for simultaneously closing all of the doors that have been opened.

11. The combination with a plurality of doors, of normally operative power means for closing all of the doors, and manually operated means carried on said doors for causing each of said power means to open any door on which pressure is exerted towards open position from completely closed position.

12. The combination with a plurality of doors, of automatic means for locking each door when the same assumes its completely closed position, means for simultaneously releasing the locks of all of the doors to permit the manual opening of any door by a person desiring to pass therethrough, means for rendering said locking means ineffective when said door has been moved from its closed position; and means for simultaneously closing all of the doors that have been opened.

13. The combination with a plurality of doors, of automatic means for locking each door when the same assumes its completely closed position, means for simultaneously releasing the locks of all of the doors to permit the manual opening of any door by a person desiring to pass therethrough, means for rendering said locking means ineffective when said door has been moved from its closed position; power devices for closing the doors, and means for simultaneously actuating said power devices.

14. The combination with a plurality of doors, of automatic means for locking each door when the same assumes its completely closed position, means for simultaneously releasing the locks of all of the doors to permit the manual opening of any door by a person desiring to pass therethrough, means for simultaneously closing all of the doors that have been opened, and means controlled by each door for rendering its door closing means inoperative when and as long as an obstruction exists during its door closing movement.

15. The combination with a plurality of doors, of automatic means for locking each door when the same assumes its completely closed position, means for simultaneously releasing the locks of all of the doors to permit the manual opening of any door by a person desiring to pass therethrough, power devices for closing the doors, means for simultaneously actuating said power devices, and means controlled by each door for rendering its door closing means inoperative when

and as long as an obstruction exists during its door closing movement.

16. The combination with a plurality of doors, of power means for controlling each of said doors, normally open power circuits for controlling the door opening and closing movements of said power means, means carried by each door to permit the manual movement thereof towards open position, means controlled thereby for closing the door opening circuit of that door, and a main control circuit for controlling said power circuits.

17. The combination with a plurality of doors, of power means for controlling each of said doors, normally open power circuits for controlling the door opening and closing movements of said power means, means carried by each door to permit the manual movement thereof towards open position, means controlled thereby for closing the door opening circuit of that door, a main control circuit for controlling said power circuits, and means actuated by the closure of said main control circuit to render said door opening circuit in a condition to be closed upon manual manipulation of the door.

18. The combination with a plurality of doors, of power means for controlling each of said doors, normally open power circuits for controlling the door opening and closing movements of said power means, means carried by each door to permit the manual movement thereof towards open position, means controlled thereby for closing the door opening circuit of that door, a main control circuit for controlling said power circuits, and means actuated by the opening of said main control circuit to automatically close the door closing circuit of each door that is open.

19. The combination with a plurality of doors, of power means for controlling each of said doors, normally open power circuits for controlling the door opening and closing movements of said power means, means carried by each door to permit the manual movement thereof towards open position, means controlled thereby for closing the door opening circuit of that door, a main control circuit for controlling said power circuits, means actuated by the closure of said main control circuit to render said door opening circuit in a condition to be closed upon manual manipulation of the door, and means actuated by the opening of said main control circuit to automatically close the door closing circuit of each door that is open.

In testimony whereof I have hereunto set my hand on this 1st day of June A. D., 1921.

HAROLD ROWNTREE.
